U.S. PATENT DOCUMENTS

1,082,423 A	12/1913	Hartman
1,951,220 A	3/1934	Tarr
2,141,093 A	12/1938	Edward et al.
2,284,352 A	5/1942	Zank
2,396,511 A	3/1946	Issigonis
2,628,657 A	2/1953	Orrick, Jr.

FIG. 1 is a front and left side perspective view of a combination center and side lamps for all-terrain vehicle embodying our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The portions of the vehicle and the vehicle components shown in broken lines form no part of the claimed design.
